ATTORNEY.

UNITED STATES PATENT OFFICE

AUGUST WARHOLOSKI, OF CEDAR RAPIDS, NEBRASKA

PLOWPOINT

Application filed December 10, 1929. Serial No. 413,017.

This invention relates to plows, and has more particular reference to an improved repair point for plow shares.

The object of the invention is to provide a very simple and efficient plow point which may be readily applied to a plow share which has become practically useless from excessive wear.

The invention consists of certain details of construction hereinafter more fully described, shown in the accompanying drawing, and claimed.

In the drawing:

Figure 1 is a side elevational view looking at the turning side of a plow share having my improved repair point applied thereto.

Figure 2 is a view similar to Figure 1, looking at the landside of the plow share.

Figure 3 is an enlarged transverse section on line 3—3 of Figure 1; and

Figure 4 is an enlarged perspective view of the present repair point before being bent and applied to the plow share.

Referring in detail to the drawing, 5 indicates a plow share with the point thereof worn away so as to shorten and gradually reduce the thickness of the turning portion as at 6 and to shorten and produce an upward depression in the lower edge of the landside portion as at 7, thereby rendering the plow practically useless.

My improved repair point comprises a wedge-shaped metallic body 8, gradually tapered narrower and increased in thickness in one direction, and provided at the narrower and thicker end thereof with a reduced extension 9 formed with an upwardly bulged intermediate portion 10 designed to engage and fit in the depression 7 of the landside portion of the plow share. The extension 9 is co-extensive with the landside edge portion of the body 8, the reduction of the extension being entirely at the side thereof remote from the landside edge of the same, and the edge portion of said extension at such side and immediately adjacent the body 8 being of inwardly curved form as at 11. The outer end portion 12 of the extension 9 is gradually reduced in thickness, while the narrow inner portion of the said extension

adjacent the body 8 is formed in its upper face with a wide and shallow transverse groove so as to provide a septum 13 of a thickness materially less than that of the adjacent portions of the body 8 and extension 9, said central portion extending at right angles to the landside edge of the body and extension to provide a line of flexing on which the extension is turned back with respect to the body when applying the repair point to the worn plow share. After the extension 9 has been properly turned back, the worn point of the share is inserted between the body 8 and the extension 9, whereupon the repair point is welded in place to the turning and landside portions of the share. The form of the repair point is such that a proper fit is had without the use of separate inserts of metal, and welding is required at only two places.

From the above description it will be seen that I have provided a plow point by means of which a worn plow share may be readily and effectively repaired.

What I claim as new is:

1. A repair plow point comprising a wedge-shaped metallic body gradually tapered narrower and increased in thickness in one direction and provided at the narrower and thicker end with a reduced extension, said extension being co-extensive with the landside edge portion of the body and formed with an upwardly bulged intermediate portion designed to fit in an upward depression worn in the lower edge of the landside portion of a plow share at the point of the latter.

2. A repair plow point comprising a wedge-shaped metallic body gradually tapered narrower and increased in thickness in one direction and provided at the narrower and thicker end with a reduced extension, said extension being co-extensive with the landside edge portion of the body and formed with an upwardly bulged intermediate portion designed to fit in an upward depression worn in the lower edge of the landside portion of a plow share at the point of the latter, the reduction of the extension being entirely at the side thereof remote from the landside

edge of the same, and the edge portion of said extension at such side being of inwardly curved form.

3. A repair plow point comprising a wedge-shaped metallic body gradually tapered narrower and increased in thickness in one direction and provided at the narrower and thicker end with a reduced extension, said extension being co-extensive with the landside edge portion of the body and formed with an upwardly bulged intermediate portion designed to fit in an upward depression worn in the lower edge of the landside portion of a plow share at the point of the latter, the narrower inner portion of said extension adjacent the body being formed in its upper face with a wide shallow transverse groove to provide a septum of a thickness materially less than that of the adjacent portions of the body and the extension, said central portion of the septum extending at right angles to the landside edges of the body and the extension to form a line of flexing on which the extension may be turned back with respect to the body.

In testimony whereof I affix my signature.
AUGUST WARHOLOSKI.
